UNITED STATES PATENT OFFICE.

EDWIN O. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

LAST.

Application filed April 17, 1922. Serial No. 553,616.

To all whom it may concern:

Be it known that I, EDWIN O. KRENTLER, a citizen of the United States, and resident of Detroit, in the county of Wayne and State 5 of Michigan, have invented an Improvement in Lasts, of which the following description, in connection with the accompanying drawings, is a specification, like letters on the drawings representing like parts.

10 My present invention is a last of the two-part type, wherein positive locking means are provided in combination with manually actuated releasing devices.

In a two-part last, having a construction 15 wherein a hinge or pivotal relative movement between the two parts is provided, it is of great importance to provide means which will hold the last rigidly and preferably positively locked while in extended 20 position, against the strains and stresses due to the various machines and processes of shoe manufacture, as at present employed. It is an important object of my present invention to provide such positive and rigid locking means in a two-part last, which will be 25 automatically actuated to hold the last firmly in extended position, which will also automatically compensate for any wear in the hinge members or any looseness in the 30 lines of cut, and which will also enable the locking means to be readily and instantly released and the last to be then easily broken or flexed to be withdrawn from a shoe.

Important features of the present invention 35 also consist in having the locking devices entirely concealed and protected from dirt, injury, damage or displacement, and with the unlocking means readily accessible, easily actuated and of simple and efficient 40 construction.

A further feature of importance in my present improved form of last consists in the fact that the positive locking devices are automatically snapped or forced into position between cooperating faces on the metallic hinge or pivotal members and while the releasing or unlocking member is manually operated when the last is flexed or shortened, the act of straightening the last 50 automatically moves the unlocking means out of the way and into position for the subsequent releasing action. Thus the simple movement of straightening the last, moving it upon its pivot into lengthened or normal 55 position, acts to throw the unlocking

devices into operative position, while simultaneously forcing the locking members into rigid, positive, holding engagement.

Further features, important details of construction and novel combinations of parts 60 and advantages will be hereinafter more fully pointed out and claimed;

Referring to the drawings, illustrating a preferred embodiment of my invention,

Fig. 1 is a side view, partly in cross-section, illustrating my improved last construction, showing the last in extended or normal position;

Fig. 2 is a similar view illustrating the last in shortened, flexed or broken position;

Fig. 3 is a fragmentary plan view, partly in cross-section on the line 3—3 of Fig 1; and

Fig. 4 is a cross-sectional view on the line 4—4 of Fig. 1.

In my present last I prefer to illustrate the same in a type of hinge last with the well known "knuckle joint" or "Kant-break" construction, and preferably of the so-called "B. B." hinge type, illustrated in U. S. 80 Patent 1,094,153, dated April 21, 1914. The hinge type of last of said patent contains important features and characteristics as therein explained, utilizing a tubular hinge member for one part, and a cooperating 85 hinge plate for the other part, and my present invention is readily applicable to a hinge last of such construction, containing all the advantages of the same, economies in construction, etc., as well as the additional 90 advantages of a positive locking and quick releasing, automatically replacing the releasing devices, etc., of the present invention.

As shown in the drawings, a typical last 95 having forepart 1 and heel part 2 is provided with the line of cut separating these two parts on the form of the "knuckle joint" type, the same being concentric, as illustrated at 5, with the main or central 100 pivot 6 uniting the two hinge members, and on which the last parts hinge or pivot for relative movement. These hinge members consist in a tubular member 7 fitted in a suitable bored recess 8 in the forepart, and a plate 9 fitted in a recess 10 in the heel part, the tube having a slot 12 through which the extending portion of the plate 9 may pass, and both being bored to receive the central pivot 6. Rivets 14 and 15 hold 110

the tube 7 and plate 9 respectively. Preferably the last is also formed with abutting faces 16 and 17, and thus far is substantially similar in construction to the present type 5 of B. B. hinge of said Patent, 1,094,153. On the part of the heel plate 9 extending forwardly or beyond the pivot 6 is formed a locking portion 20, consisting in the forward projection and concave face 21. Co- 10 operating and interlocking therewith is a headed bolt 25 having a head portion 26 of suitable contour to fit within the curved face 21 and projecting locking part 20 of the heel plate 9. A spring 30 normally acting 15 between the rivet 14 and the head of said bolt 25, forces the bolt into engagement with the said projecting or forward portion of the plate 9. Thus when the last is in extended position, the bolt 25 is held firmly 20 against the end portions of the plate 9 by the spring 30 and the cooperating faces act to positively and rigidly interlock and hold the last in its extended position. It will be appreciated that lasts in use are presented 25 to levelling, beating, heel nailing and lasting machines, and the like, bottom upward, and therefore the strains are against the bottom of the last. The cooperating locking faces of the plate 9 and bolt 25 are so formed as 30 to resist all such strains and to hold the last rigidly in extended or locked position. In order to unlock the last it is necessary to release the locking action of said bolt and cooperating faces on the plate 9, and for 35 this purpose I provide a simple construction of releasing lever. Where the plate 9 and tube 7 overlap to allow for the common pivoting on the pin 6, I form the slot 12 in the tube 7 of sufficiently greater width 40 than the thickness of the plate 9 to receive the legs 35 and 36 of a releasing lever 40, said legs straddling the plate 9 and having therein an elongated slot 37 which also straddles the pin 6. The forward ends of these 45 legs 35 and 36 are formed as projections 38 bearing against the head 26 of the bolt 25 on either side of the plate. I also form in the plate 9, directly over the pivot 6, a notch or recess 41, in which the lower part of the 50 lever 40, where the legs 35 and 36 join, are seated or straddled across the same as a bearing. Thus on movement of the lever 40, with the bearing in the notch 41 as a fulcrum, the legs 35 and 36 will be moved 55 forwardly and backwardly for the limit of length permitted by the slot 37. The spring 30 is of sufficient power to force the bolt 25 into its locking engagement and also to rock this lever so that when the last parts are 60 moved into extended position, as shown in Fig. 1, the spring 30 will force the bolt into locking engagement with the parts 20 and 21 of the plate 9, simultaneously moving the lever 40, rocking it upon the fulcrum above 65 described and moving same on the pivot 6,

the distance allowed by the slot 37. The last in this position is firmly, rigidly and positively locked. To release the lock the operator simply catches the lever 40 and moves it backwardly, thus removing the head of the bolt 25 against the tension of its spring 30, this releasing the cooperating lock engaging portions, and thereupon the forward and heel part may be moved on the pivot 6 freely and easily, the forward portions 38 of the legs 35 and 36 effecting this releasing action, as will be readily understood. To provide for a sufficient "throw" of the lever 40, I may form a recess 44 in the heel part, as illustrated. 70 75 80

In the operation of the last the mere movement of the last parts into extended position effects the locking and the automatic repositioning of the unlocking or releasing lever into proper position so that its movement to the right, viewing the drawings, releases the spring and effects the unlocking, thereby permitting a quick and easy flexing of the last, as well as speedy removal of the last from the shoe. Heretofore it has been necessary to exert considerable strength to break or flex the last and this has been exerted through the completed shoe, subjecting it to some strains, whereas by my present invention, no strains whatever are exerted through the shoe to break the last, and the last can be withdrawn much quicker than was formerly possible in utilizing hinge lasts of this type. Furthermore an important advantage is that the spring 30 required in my present last, is of much less power and hence very much more economical than is necessary in utilizing a strong spring necessarily of sufficient power to prevent breaking of the last, in the construction shown in said Patent 1,094,153. 90 95 100 105

In assembling the parts, my present invention also possesses great advantages. The last parts are readily moved into assembled position and held there by slight force, the lever 40 is positioned with the legs 35 and 36 straddling the forward part of the plate 9, and with the parts in this position, the tube 7, locking lever, and plate 9, are all assembled and keyed by the fitting of the pivot 6. Thus the hinge members are easily united, the parts being in the position shown in Fig. 1 with the spring 30 not under great compression. In the action of the unlocking of my present last, the movement of the lever 40 is only necessary for a very slight distance, separating the bolt 25 from locking engagement, a slight separation then permitting the flexing of the last, which is completed by the sliding of the projecting portion 20 on the plate 9 against the rounded surface of the head 26 of the locking bolt. Thus the completion of the flexing or breaking of the last is effected merely by the movement of the heel 110 115 120 125 130

and forepart, and the lever 40 housed within the recess 44 without being forced therein by the operator. In other words it is only necessary to initiate the releasing action by 5 a slight quick movement of the lever 40, and simultaneously starting a relative movement of the forepart and heel part on the pivot 2, the bolt 25 being thus moved sufficiently to permit the completion of the flex- 10 ing action as above explained.

My improved locking and releasing construction has the important advantages of all the locking members being concealed within the interior of the last, protected 15 from damage or dirt, producing a locking engagement on the metallic members constituting the hinge, and the thrust of the spring 30 and the cooperating bearings of the curved head 26 and face 21, providing for 20 a considerable range or scope of compensation for wear or slight looseness in the lines of cut or the pivot. In carrying out this feature it will be noted that the curved face 21 on the lever 9 is formed on an arc 25 of greater radius than is the curved surface of the head 26 on the locking bolt, thus producing a construction wherein the constant tension of the spring 30 thrusts the bolt 25 forwardly without fairly seating 30 the head of said bolt against any stop or limit on the face 21.

In my improved last are the further advantages of riveting or anchoring the hinge plate members as shown at the rivets 14 35 and 15, remote from the line of cut dividing the two parts, and in the solid wood portion of each part. My releasing construction, while particularly applicable to an interlocking member which is normally held in 40 position by a spring, as herein shown, is also equally applicable to release the interlocking engagement of such a construction as is shown in Patent 1,410,477, issued March 21, 1922, if desired, or any similar hinge 45 last construction wherein it is desired to release the locking of the last in extended position prior to the flexing or breaking of the last to shorten it.

My invention is further described and defined in the form of claims as follows:

1. A two-part last, having hinge members uniting said parts, a movable locking member and means cooperating with one of said hinge members to interlock with the locking member to hold the last rigidly in extended position, the said interlocking members being concealed and protected within one of the hinge members and being formed and constructed to compensate automatically 55 for wear.

2. A two-part last, having hinge members uniting said parts, one member being in the form of a tube, a movable locking member concealed in said tube and adapted to 60 cooperate with the other hinge member to

rigidly lock the last in extended position, in combination with an unlocking means manually operable to separate the interlocking action of said members prior to flexing of the last.

3. A hinge last, having a bored recess in one part, a tubular hinge member fitted in said recess, a plate member secured to the other part, said two members being united on a pivot on which the last parts may be 70 moved, a bolt movable within said tubular member, having means to interlock with a cooperating engaging face on the plate hinge member, means normally forcing said bolt into interlocking engagement with said 75 plate member, and manually movable means extending outside the hinge members to release the bolt from interlocking position.

4. A hinge last, having a bored recess in one part, a tubular hinge member fitted in 80 said recess, a plate member secured to the other part, said two members being united on a pivot on which the last parts may be moved, a bolt movable within said tubular member, having means to interlock with a 85 cooperating engaging face on the plate hinge member, means normally forcing said bolt into interlocking engagement with said plate member, and manually movable means extending outside the hinge members having 90 a lever, and fulcrumed on one of said hinge members.

5. A hinge last, having a bored recess in one part, a tubular hinge member fitted in 100 said recess, a plate member secured to the other part, said two members being united on a pivot on which the last parts may be moved, a bolt movable within said tubular member, having means to interlock with a 105 cooperating engaging face on the plate hinge member, means normally forcing said bolt into interlocking engagement with said plate member, and manually movable means to release the bolt from interlocking action 110 consisting in a hand-operated lever extending outside the hinge members, a portion straddling the plate hinge and bearing thereon, and extending portions adapted to contact with the bolt, whereby movement of the lever will release the bolt from interlocking engagement.

6. A hinge last, having a bored recess in one part, a tubular hinge member fitted in 115 said recess, a plate member secured to the other part, said two members being united on a pivot on which the last parts may be moved, a bolt movable within said tubular member, having means to interlock with a 120 cooperating engaging face on the plate hinge member, means normally forcing said bolt into interlocking engagement with said plate member, and manually movable means to release the bolt from interlocking action 125 consisting in a hand operated lever extending outside the hinge members, a portion 130

straddling the pivot, and bearing on a hinge member, and extending portions adapted to contact with the bolt, whereby movement of the lever will release the bolt from interlocking engagement.

7. A hinge last, having a bored recess in one part, a tubular hinge member fitted in said recess, a plate member secured to the other part, said two members being united 10 on a pivot on which the last parts may be moved, a bolt movable within said tubular member, having means to interlock with a cooperating engaging face on the plate

hinge member, means normally forcing said bolt into interlocking engagement with said plate member, and manually movable means to release the bolt from interlocking action consisting in a hand-operated lever extending outside the hinge members, a portion straddling the plate hinge and bearing thereon, and extending portions adapted to contact with the bolt, said straddling portions being slotted to engage the pivotal pin.

In testimony whereof, I have signed my name to this specification.

EDWIN O. KRENTLER.
